ATTORNEY

UNITED STATES PATENT OFFICE.

GEORGE T. TURNER, OF PHILADELPHIA, PENNSYLVANIA.

DESIGN FOR AN AUTOMOBILE-FRAME.

SPECIFICATION forming part of Design No. 33,003, dated July 24, 1900.

Application filed May 16, 1900. Serial No. 16,926. Term of patent 14 years.

To all whom it may concern:

Be it known that I, GEORGE T. TURNER, a citizen of the United States, residing at Philadelphia, in the county of Philadelphia and State of Pennsylvania, have invented 5 and produced a new and original Design for an Automobile-Frame, of which the following is a specification.

Reference is had to the accompanying drawing, forming part hereof, in which the figure is a perspective view of my new frame.

As shown in the drawing, my design consists of upper bars A and B, each of which is practically straight for a suitable distance— 15 say from x' to x^2 . Then from x^2 they have a general forward and upward direction. From x' backward they have a backward upward direction to a connecting rod or brace C, to which they are secured at $c' c^2$, the general 20 outline of said upper bars being an elongated U shape. It also consists of lower bars D and E, which are of the same outline as A and B from x' forward, but from said point

backward they do not follow the direction of the upper bars and terminate in suitable 25 holders for the axle-hangers, being supported by struts G and H and also by means of the brace I, the general rear direction of said upper and lower bars forming a Y shape at each side of the frame. The upper and lower 30 bars are attached to each other by uprights J and K, and to the forward ends of the said bars are secured beads L L' for the steering-bars of an automobile.

Having described my invention, what I 35 claim as new, and desire to secure by Letters Patent, is—

The design for an automobile-frame herein shown and described.

In testimony whereof I affix my signature 40 in presence of two witnesses.

GEORGE T. TURNER.
